UNITED STATES PATENT OFFICE.

RAYMOND F. STOCKTON, OF BURBANK, CALIFORNIA.

SHOE SPRING LACE.

Application filed December 9, 1925. Serial No. 74,912.

My invention is a shoe spring lace and a shoe construction adapted to utilize such lace and in the manner of fastening the lace to the shoe.

5 An object of my invention is to provide a shoe spring lace which may be attached to a shoe in the place of the ordinary lace and may simulate in parts such lace in appearance, the shoe spring lace holding the 10 shoe in firm position on the foot as if tightly laced, but allowing a certain resilience of movement not allowable with the inextensible type of lace.

My invention also comprises a shoe construction adapted to allow use of a spring lace and also a construction which will allow the fitting of old shoes with my attachment, whereby they may be utilized with my spring type of lace.

20 My invention also comprises the manner of attaching the lace to the shoe, this giving either a permanent or a detachable fastening and also preferably a covering for the lace with the tongue of the shoe.

25 My shoe spring lace considered generally consists of a small coiled wire spring which is preferably covered by some suitable extensible fabric, the ends of the spring having means to attach them to a shoe to opposite sides of the upper at the usual split for lacing and covering the tongue. I construct the shoe with a flexible wire extending upwardly in the upper on each side of the lacing split and have eyelets through 30 which the ends of the spring may extend to be engaged by the wire.

Another feature of my invention comprises a tongue having a series of transverse openings so that the lace may extend 40 through such openings in the tongue.

My invention will be more readily understood from the following description and drawings, in which;

Figure 1 is a perspective view of a shoe 45 having my spring shoe lace.

Fig. 2 is an enlarged view of the upper at the lacing split, showing the type of lace and the manner of attaching it to the shoe.

Fig. 3 is a section of the shoe on the line 50 3-3 of Figs. 1 or 2.

Fig. 4 is a transverse section on the line 4-4 of Fig. 2, showing the lace engaging the tongue.

Fig. 5 is a side view of one of the individual laces.

Fig. 6 is a longitudinal section of one of 55 the laces.

Fig. 7 is a side view of a modified form of disconnectible two part lace.

Fig. 8 is a side view of another form of 60 spring shoe lace.

Fig. 9 is a section of a shoe showing such lace engaging the ordinary eyelets of a shoe.

My shoe spring lace is designated generally by the numeral 1 and is attached to the upper 2 of the shoe at each side of the lacing 65 split 3, the shoe having a special lace engaging structure 4 incorporated therein and the lace having a special type of connection 5 to the tongue 6.

The construction of the spring lace is sub- 70 stantially as follows, having reference particularly to Figs. 2, 3, 5 and 6:

A coiled wire spring 7 has the opposite ends of the spring extended in an axial direction as indicated by the numeral 8, the 75 extreme ends being bent laterally as indicated by 9 and having an eye 10 formed thereon. A covering or casing 11 of a woven fabric or some stretchable composition is secured over the spring to enclose 80 it from view. If a fabric covering is utilized, it should be such as to allow stretching and the fabric returning to its normal relation after contraction of the spring.

My novel type of shoe construction is in- 85 dicated particularly in Figs. 1, 2 and 3, in which the wires 12 are fitted in pockets 13 on opposite sides of the lace split in the upper, there being a stitching 14 at the top of the shoe to close the pockets and stitching 15 at the lower end to prevent the wire working downwardly. Small eyelets 16 are 90 formed in the leather of the upper, leading into the pockets 13. These may be formed with metallic eyelets or the so-called invisible type, in which holes in the leather are formed with the metal eyelets being inside or else in this construction the metal eyelets may be discarded.

The manner of attaching the spring lace 100 to the wires is by means of the eyes 10 on the ends of the springs engaging the wires 12, while these are being thrust into the pockets. The ends of the springs having the eyes 10 are thrust through the eyelets 105 16 or through the openings in the leather and the wires are passed through the eyes 10.

It will be understood that the spring

laces will be sufficient in number and spaced in the upper in substantially the same manner as the present type of cord or leather lacings.

5 The tongue fastening 5 is constructed by forming openings 17 in the tongues, the material of the tongue being pressed outwardly as indicated at 18 so that the laces may have a central section passing through 10 the hole in the lace as indicated by the numeral 19, the back part 20 of the lace extending behind the upper at each side of the lacing split.

Thus it will be seen that the spring laces 15 retain the tongue in its proper position and preferably each lace is passed through the tongue, thereby forming a neat appearing as well as useful construction of the lace fastening to the tongue.

20 In the construction of Fig. 7, the lace is formed in two sections 21 and 22; each of these being internally of the same construction as in Figs. 5 and 6 and with one end 25 forming an eye 10, the other end of the spring of one lace section has an eye 23 and the other has a hook 24 adapted to engage therewith so that these hooks and eyes may be engaged to hold the lace firmly connected and the upper being tightly drawn in the 30 split. In this construction it is preferably and more sightly to have the hooks and eyes 23 and 24 behind the openings in the tongue.

In Figs. 8 and 9 I illustrate an adaptation of my spring shoe lace to be utilized 35 with an ordinary shoe having eyelets. The lace has a coiled spring 7 with hooks 25 at each end. These hooks are adapted to engage in the ordinary eyelets 26 of a shoe; the tongue of the shoe 27 in this case extending 40 behind the upper and not over the lace as shown in Fig. 2.

It will be apparent that this construction of Figs. 8 and 9 could be utilized to engage the lacing hooks attached to the shoe 45 as well as to engage the eyelets.

Although my invention is of a simple construction, nevertheless the spring shoe lace may be modified considerably to suit different types of shoes or to adapt it to 50 various ornamental constructions. For instance, the spring could be made of a flattened type instead of having as shown, circular helical coils. The type of fastening

by the wire 12 as shown in Fig. 2, may be built into the shoe in the factory while the 55 shoe is being made or a pocket may be made in the lining of old shoes by running stitches in the lining and inserting a wire therein enclosing it in by a stitching similar to 14 at the top of the upper.

60 It will be obvious that other types of fastening may be utilized as well as the wire. Moreover, the tongue 6 may be engaged by the fastening in a different manner from that shown, this fastening being designed 65 to keep the tongue in proper relation to the split portion of the upper. It will be apparent moreover, that such a form of tongue could be utilized with ordinary lacings and if it is desired to make a water 70 proof tongue for water proof boots the outer pressed portion 18 of the tongue which may be designated as straps could be sewn to the tongue, thereby holding the tongue in proper relation to the ordinary inex- 75 tensible laces.

Such changes would be within the spirit of my invention as set forth in the description, drawings and claims.

Having described my invention, what I 80 claim is:

1. In a shoe lace, an upper having a split, a tongue positioned behind said split, there being transverse openings formed in the tongue, outwardly pressed portions of the 85 tongue at said openings, said portions extending into the split, and spring lacings extending through the said openings, fitting in the outwardly pressed portions, said lacings being secured to opposite sides of 90 the upper.

2. In a shoe lacing, a shoe upper having a split, flexible wires in the upper at each side of the split, said wires being secured in pockets, a tongue positioned behind the 95 split, there being transverse openings formed in the tongue with outwardly pressed portions, said portions extending into the split, spring lacings extending through the openings, and the outwardly 100 pressed portions of the tongue, and being secured at their opposite ends to the flexible wires in the upper.

In testimony whereof I have signed my name to this specification.

RAYMOND F. STOCKTON.
